K. BAUMANN.

CONDENSER.

APPLICATION FILED OCT. 2, 1918.

Patented July 20, 1920.

UNITED STATES PATENT OFFICE.

KARL BAUMANN, OF URMSTON, ENGLAND, ASSIGNOR TO THE BRITISH WESTINGHOUSE ELECTRIC AND MANUFACTURING COMPANY, LIMITED, A COMPANY OF GREAT BRITAIN.

CONDENSER.

1,347,436.

Specification of Letters Patent.

Patented July 20, 1920.

Original application filed January 31, 1917, Serial No. 145,706. Divided and this application filed October 2, 1918. Serial No. 256,577.

To all whom it may concern:

Be it known that I, KARL BAUMANN, a citizen of the Confederation of Switzerland, and a resident of Urmston, in the county of 5 Lancaster, England, have invented a new and useful Improvement in Condensers, of which the following is a specification, this application being a division of application Serial No. 145,706, filed January 31, 1917.

10 This invention relates to condensers and more particularly to that class of condensers used in connection with steam turbines, and has for an object the production of a condenser wherein the expansion joint, usually 15 employed between the condenser shell and the exhaust casing of the turbine is rendered unnecessary.

Another object of the invention is the 20 production of a condenser wherein the condensing surface for the tube nest may be brought nearer to the last row or rows of blades from which the steam leaving the turbine flows, thus shortening the path for the steam flowing from the turbine and reducing the height of the combined 25 condenser and turbine.

Further objects are the production of a condenser wherein certain portions of the shell of the condenser are supported by the 30 turbine casing, while the heavier parts of the condenser, such as the cooling tubes and their supports are carried by suitable foundations; the production of a condenser of the above type wherein the tubes and sag 35 plates are supported by the ends of the condensers and such other objects as will herein-after appear. Certain embodiments of the invention are illustrated in the accompanying drawings, wherein—

40 Figure 1 is a transverse sectional view of the condenser; Fig. 2 is a longitudinal sectional view of the condenser and Fig 3 is a fragmental section of a modified form of the flexible joint construction illustrated in 45 Figs. 1 and 2.

Referring to the drawings; 4 indicates a steam turbine, to which the central section of the condenser shell 5 is attached directly, so that the path of the steam from the turbine to the condenser is made as direct and as short as possible. This section of the condenser, however, is the only portion thereof carried by the turbine casing and is

supported in contact therewith by atmospheric pressure due to the vacuum existing 55 within the condenser and the exhaust casing of the turbine, and by suitable bolts which secure the condenser to the exhaust casing of the turbine.

The end members 6 and 7 are supported 60 independently of the shell 5 upon foundations 8 and are flexibly connected to the rigid shell 5 by means of flexible corrugated cylindrical sections 9 so as to permit universal relative movement of the central shell 65 5 with respect to the end members 6 and 7. It will readily be seen that the central shell is free to expand in all directions without disturbing the ends of the condenser.

The condenser ends 6 and 7 are each provided with a tube plate 10 to which the cooling tubes 11 are connected in a well known manner so as to form a surface condenser. Cooling water is circulated through the tubes 11, first entering the water box 12 75 through the inlets 13 and passing through the upper tubes to the water box 14 and back through the lower tubes to the water box 15 and out through the outlets 16.

The ends of the condenser are supported 80 so as to oppose the atmospheric pressure tending to collapse the flexible sections 9, by means of a vertical web or compression member 17 extending the entire length of the tube nest and connecting the tube plates 85 10. The tubes 11 are supported intermediate the tube plates by one or more sag plates 18, (one of which is shown) through which the tubes pass, and these plates are bolted or otherwise secured to the web 17, so 90 that the weight of the intermediate mechanism of the condenser is not imposed upon the shell 5. The sag plates also serve to reinforce the web 17. Aside from the special construction of the condenser shell and 95 its element, the condenser operates in a manner similar to the other condensers of like type. Fluid enters the top of the condenser and is condensed by contact with the cooling tubes; the condensate being drawn 100 off through a hot well outlet 19, which may be flexibly connected to any suitable pumping apparatus. The air is drawn off from the usual air outlet 20.

Fig. 3 shows a modified form of expansion joint which may be used instead of the

form shown in Fig. 2. It will be seen that the flexible portion 9' is simply given a different contour than the joint 9.

- It will be apparent from the foregoing 5 that while the complicated and expansive expansion joint usually placed between the exhaust casting of the turbine and the condenser has been eliminated, the condenser shell 5 is free to expand vertically and horizontally to take care of the expansions and contractions due to changes in temperature of the shell or from other causes.

While I have described and illustrated 10 but two embodiments of my invention, it 15 will be apparent to those skilled in the art that various changes, modifications, additions and omissions may be made in the apparatus described and illustrated without departing from the spirit and scope of the 20 invention, as set forth by the appended claims.

What I claim is:

1. A steam condenser for turbines comprising a horizontal shell adapted to be 25 supported at its central portion by the turbine and at its end portions independently of the turbine and provided with means whereby axial displacement of its central portion with respect to the end portions 30 is permitted.

2. A steam condenser for turbines comprising a horizontal shell adapted to be supported at its central portion by the turbine and at its end portions independently 35 of the turbine and embodying flexible portions between the supported portions.

3. A steam condenser for turbines comprising a horizontal shell adapted to be supported at its central portion by the turbine and at its end portions independently 40 of the turbine and provided with means whereby universal displacement of its central portion with respect to the end portions is permitted.

4. A steam condenser for turbines comprising a shell having a rigid central section adapted to be attached to the turbine, end sections supported independently of the 45

turbine, and flexible portions connecting the end sections with the rigid central section. 50

5. A condenser for turbines comprising a central section adapted to be supported by the turbine, end sections flexibly secured to the central section and supported independently of the turbine, and cooling tubes extending through the central section and supported by the end sections. 55

6. A condenser for turbines comprising a central section adapted to be attached to the turbine, end sections flexibly secured to the central section and supported independently of the turbine and cooling tubes extending through the central section and supported by the end sections. 60

7. The combination with a steam condenser for turbines comprising a shell, the central portion of which is secured to the turbine and the end portions of which are flexibly connected to the central portion and are supported independently of the turbine, 70 of a nest of cooling tubes supported by the end portions, so that the central portion may move independently of the tubes. 75

8. A condenser for turbines comprising a central shell adapted to be supported by the turbine, end members flexibly secured to the shell and supported independently of the turbine, and a compression member carried by the end members and extending through the central shell. 80

9. A condenser for turbines comprising a central shell adapted to be supported by the turbine, end sections flexibly secured to the shell and supported independently of the turbine, cooling tubes extending through the shell and supported at their ends by the end sections, a compression member connecting the end sections and preventing relative displacement thereof and a sag plate for the tubes supported independently 85 of the central shell and upon the compression member. 90

In testimony whereof I have hereunto subscribed my name this tenth day of September, 1918.

KARL BAUMANN.
